His Attorney.

UNITED STATES PATENT OFFICE.

JOSEPH J. JANCA, OF ST. LOUIS, MISSOURI, ASSIGNOR TO THE EMERSON ELECTRIC MFG. CO., OF ST. LOUIS, MISSOURI, A CORPORATION OF MISSOURI.

SHORT-CIRCUITING MECHANISM.

Application filed December 24, 1925. Serial No. 77,646.

This invention relates to short circuiting mechanism and consists in the novel construction hereinafter disclosed.

An object of the invention is to provide a short circuiting unit adapted to be operated by centrifugal force, which unit is arranged for convenient assembly with the armature shaft so that it may be readily installed and removed.

Another object of the invention is to provide a positively acting short circuiting mechanism that will operate accurately at predetermined speeds and which may be easily adjusted to operate at different predetermined speeds.

Additional advantages of the construction will be readily apparent from the following detailed description thereof, taken in connection with the accompanying drawing in which

Fig. 1 is an elevation of an armature showing the improved short circuiting mechanism installed therewith;

Fig. 2 is an end elevation;

Fig. 3 is a view partially in vertical section;

Fig. 4 is a face view of the contact disk;

Fig. 5 is a view of the actuator for the disk;

Fig. 6 is a view of a retaining plate; and,

Fig. 7 is a view of the actuating arms with their supporting rings.

In the embodiment of the invention illustrated in the drawing, I have shown the invention as associated with an armature 1 of usual construction, having an armature shaft 2. On the armature shaft is a ring 3 arranged to support the commutator segments 4.

The short circuiting of the armature is accomplished by actuating a contact disk inwardly against the vertical faces of the commutator segments. The contact disk comprises a ring 5 having a plurality of spaced fingers 6 which are curved inwardly towards the vertical faces of the commutator segments when the disk is assembled.

The armature shaft carries an elongated collar 7 that extends at one end within the mounting 3 for the commutator segments and outwardly at the other end beyond the vertical plane of the commutator segments. This collar has at its inner end a flange 8. The support for the actuator arms is in the

form of a ring 9 having equally spaced pairs of ears 10 formed integral therewith, said ears having overturned ends forming eyes for a pivot pin. Pivottally connected with each pair of ears 10 is an arm 11 having an eye 12 formed at its inner end. The inner end of each arm extends between its respective pair of ears 10 and a pivot pin 13 serves to connect the arms with the support, so that the outer ends of the arms may move radially in respect of the axis of the armature shaft.

The support for the arms 11 is fast on the collar 7 and an expansion spring 14 is interposed between the ring 9 and a retaining ring 15 mounted loosely on the collar 7, which ring 15 abuts against the ring portion 5 of the contact disk. The retaining ring is provided with a series of notches 16 through which the arms 11 extend, and also with a series of forwardly extending arms 17 that project through the opening in the ring 5 and upon which said ring is supported. The forward ends of the arms 17 are arranged to extend across the edge of the actuator for the contact disk between the arms thereof, thus serving to prevent this member from rotating with the contact disk which is free to revolve on the arms 17.

The actuator for the contact disk comprises a spider having a center portion 18 adapted to fit over the collar 7 and arms 19 each of which is bent to form a transverse shoulder 20 and a flange 21. Each arm 19 is provided with an opening 22 through which the arms 11 extend. The arms 11 have their outer ends turned backwardly to form loops 23 in which the reduced portion 24 of rollers 25 are seated. A spacing washer 19^a is interposed between the ring portion 18 of the actuator and the retaining plate 15, thus permitting the contact disk to revolve independently of the actuator.

In assembling the device, the supporting ring 9 of the actuating arms with the arms 11 mounted thereon is fitted over a reduced end of the collar 7, which reduced end is then coined over against the ring 9, thereby rigidly securing the ring 9 to the collar 7. The spring 14 is then mounted over the collar 7 and the retaining member 15 interposed against the outer end of the spring, the arms 11 seating in the notches 16 of the ring. The contact disk 5 is then fitted over

the ears 17 and the actuator 18 is assembled. After the assembly of these parts, the rollers are mounted by connecting the loops 23 over the reduced portion 24 of said rollers. The 6 normal action of the spring 14 is to hold the rollers inwardly of the shoulders 20 of the arms 19. When the armature shaft has attained the predetermined speed, the free ends of the arms 11 will move radially 10 outwardly and the rollers will snap over the shoulders 20, moving the actuator inwardly against the contact disk 5, thereby forcing the fingers 6 into contact with the vertical faces of the commutator segments and thus 15 short circuiting the armature.

The adjustment of the short circuiting mechanism so that it will operate at predetermined speeds may be accomplished by varying the weight of the rollers 25, or by 20 varying the tension of the spring 14. The rollers 25 may be made of different weights and the spring 14 of different tension, and, as both the rollers and spring may be readily changed, the adjustment for different 25 speeds may be easily accomplished.

It is apparent from the foregoing that the device is simple in construction, positive in 30 operation, and that it may be readily assembled and disassembled for the purpose of repair, replacement or adjustment.

I am aware that the invention may be modified in certain particulars without departing from the spirit and scope thereof and I do not limit myself, therefore, to the 35 exact construction or to the preferred embodiment of the invention, but what I claim and desire to secure by Letters Patent is:—

1. A short circuiting mechanism comprising 40 a contact member movable to make and break contact with commutator segments, an actuator for moving the contact member to contact with the commutator segments, a plurality of arms each pivoted at one end and having its other end free, and a roller 45 connected to and movable with the free end of each of said arms and arranged to operate by centrifugal force to engage and move said actuator and thereby said contact member into contact with the commutator segments.

2. A short circuiting mechanism comprising 50 the combination of an armature shaft and a commutator having commutator segments with faces disposed transversely of the axis of the shaft, a support mounted on the shaft, arms pivoted to said support, a contact disk arranged transversely of the shaft, an actuator for moving said disk toward the contact 55 faces of the commutator segments, means normally actuating said actuator outwardly from the contact faces of the commutator segments, and rollers releasably supported by the free ends of said arms adapted to move radially of the axis of the shaft when 60 the shaft is rotated and to engage and move

said actuator longitudinally of the armature shaft thereby moving said disk into contact with the commutator segments.

3. A short circuiting mechanism comprising 65 the combination of an armature shaft, a commutator having faces transversely disposed in respect of the shaft, a contact member arranged to be moved into contact with the contact faces of the commutator segments, an actuator for said contact member, 70 said actuator having a cam face, a plurality of arms, a support for said arms for pivotally connecting one end thereof with the armature shaft, rollers connected to and movable with the free end of said arm 75 adapted to cooperate with the cam face of said actuator, and means holding the rollers in contact with said cam face of the actuator.

4. A short circuiting mechanism comprising 80 the combination of an armature shaft, a commutator having contact faces disposed transversely of the shaft, a support carried by the shaft, arms pivoted to the support and having their free ends extending outwardly from the contact faces of the commutator, a contact disk intermediate of the free 85 ends of the arms and the faces of said commutator, an actuator between the free ends of said arms and said contact disk, a spring normally moving the actuator outwardly 90 from the commutator, and rollers releasably supported by the free ends of said arms arranged to contact with said actuator and to move the same inwardly against the contact disk when the shaft is rotated at a predetermined speed, said rollers also serving to hold the parts in assembled relationship.

5. A short circuiting mechanism comprising 95 the combination of an armature shaft, a commutator having contact faces disposed transversely of the shaft, a support carried by the shaft, arms pivoted to the support and having their free ends extending outwardly from the contact faces of the commutator, a contact disk intermediate of the free 100 ends of the arms and the faces of said commutator, an actuator having cam faces disposed between the outer extremity of the arms and the contact disk, a spring normally retracting the contact disk from the commutator, and rollers carried by the free ends of 105 said arms arranged to make contact with the actuator, said rollers being adapted to ride over said cam faces when a predetermined speed has been attained by the armature shaft, thereby causing said actuator to actuate the contact disk into contact with the contact faces of the commutator.

6. A short circuiting mechanism comprising 110 the combination of an armature shaft, a commutator having faces in a plane crossing the axis of said shaft, a support fast on the shaft, a retaining device, a spring 115 interposed between said retaining device and said support normally actuating said device 120

125

- outwardly from the contact faces of the commutator, arms pivoted to said support at one end and being free to move radially of the armature shaft at the opposite end, 5
 5 a contact member carried by said retaining device arranged to revolve independently of the armature shaft, a device for actuating the contact member into contact with the contact faces of the commutator, and rollers
 10 carried by the free ends of said arms operatively connected with the actuator for moving the same, whereby the contact member will be caused to make and maintain contact with the commutator when the armature shaft has attained a predetermined speed.
 15 7. A short circuiting mechanism comprising the combination of an armature shaft, a commutator having contact faces, a supporting element loosely supported by the shaft, a member supported by said supporting element for movement to and from contact with said faces, an actuator for moving said member into contact with said faces, a
 20 series of arms extending through said member and said actuator and having their inner ends pivoted for outward swinging movement, and an element on the outer end of each of said arms operated by centrifugal
 25 force resulting from the rotation of said shaft to move said actuator in a direction to move said member into contact with said faces.
 30 8. A short circuiting mechanism comprising the combination of an armature shaft, a commutator having contact faces, a supporting element loosely supported by the shaft, a member supported by said supporting element for movement to and from contact with said faces, an actuator for moving said member into contact with said faces, a series of arms extending through said member and said actuator and having their inner
 35 ends pivoted for swinging movement away
 40 from the axes of the shaft, an element on
 45 the outer end of each of said arms operated by centrifugal force resulting from the rotation of said shaft to move said actuator in a direction to move said member into contact with said faces, and a spring acting to move said member out of contact with said faces when the armature shaft stops.
 50 9. A short circuiting mechanism comprising the combination of an armature shaft, a commutator having contact faces, a contact member movable longitudinally of the shaft and adapted to make and break contact with said contact faces of the commutator segments, and a device for actuating said contact member including an arm normally extending longitudinally of the shaft, said arm being pivoted at one end, a roller carried by the free end of said arm and movable outwardly with said arm when the armature shaft is rotated at a predetermined speed, and connections between said contact member and said roller for moving said contact member into contact with said contact faces when said armature shaft is rotated at a predetermined speed.
 55 10. A short circuiting mechanism comprising the combination of an armature shaft, commutator segments having faces transversely disposed in respect of the shaft, a contact member arranged to be moved into contact with the contact faces of the commutator segments, a plurality of arms extending longitudinally of the armature shaft and pivoted at one end for swinging movements in radial planes, a weighted member carried by the outer extremity of each of said arms and movable in radial planes therewith by the rotation of the armature shaft, and an element operated by said weighted members to move said contact member into contact with said contact segments of the commutator faces when said armature shaft is rotated at a predetermined speed.
